(57) **CLAIM**

The ornamental design for a hand-held light, as shown and described.

DESCRIPTION

FIG. 1 is a perspective view of a hand-held light, showing our new design;

FIG. 2 is a front elevational view thereof, the rear elevational view being identical thereto;

FIG. 3 is a top plan view thereof;

FIG. 4 is a bottom plan view thereof;

FIG. 5 is a right side elevational view thereof, the left side being identical thereto; and,

FIG. 6 is a cross-sectional view taken along 6-6 of FIG. 5. The broken lines illustrate environmental structure and form no part of the claimed design.
